UNITED STATES PATENT OFFICE.

ALBERT H. FORGER, OF NEW MARTINSVILLE, WEST VIRGINIA.

HEADLIGHT-LENS.

1,251,211.

Specification of Letters Patent.

Patented Dec. 25, 1917.

Application filed October 20, 1917. Serial No. 197,579.

To all whom it may concern:

Be it known that I, ALBERT H. FORGER, a citizen of the United States, residing at New Martinsville, in the county of Wetzel and State of West Virginia, have invented 5 certain new and useful Improvements in Headlight-Lenses, of which the following is a specification.

My invention relates broadly to lights, 10 such as head lights, adapted for use upon vehicles or automobiles, while not necessarily restricted to this use, and has particular reference to improvements in the construction of the lenses thereof, to eliminate 15 the blinding effect produced by such lights, without unduly reducing the shafts of light, thrown from the lamps, at a suitable distance in advance of the same or the automobile, upon the road bed.

20 An important object of the invention is to provide a lens of the above mentioned character, having means whereby a diffused or non-glaring light is produced near or in proximity to the automobile, and shafts of 25 light are properly bent downwardly and thrown upon the road bed, at a suitable distance from the automobile, without producing shafts of light which are bent upwardly, which would shine in the eyes of a pedestrian and the like, thus producing a blinding 30 effect.

A further object of the invention is to provide a lens of the above mentioned character, 35 having substantially horizontally arranged prisms, provided with inclined and approximately horizontal faces, the inclined faces serving to bend the shafts of light downwardly and the approximately horizontal faces being frosted, painted, or otherwise 40 rendered translucent or opaque.

Other objects and advantages of the invention will be apparent during the course of the following description.

In the accompanying drawings forming 45 a part of this specification and in which like numerals are employed to designate like parts throughout the same,

Figure 1 is a central vertical sectional view through a lens embodying the invention, showing the same in use,

Fig. 2 is an inner side elevation of the same,

Fig. 3 is a horizontal sectional view taken on line 3—3 of Fig. 2, and,

55 Fig. 4 is an enlarged vertical fragmentary

section through the horizontal prisms of the lens.

In the drawings, wherein for the purpose of illustration is shown a preferred embodiment of my invention, the numeral 5 designates a lens of suitable size to fit in the casing of a headlight of an automobile, while the lens may be made in any suitable size. This lens is preferably formed of transparent glass. Arranged behind the lens 5 is a 60 parabolic reflector 5' with an electric lamp or bulb 6', disposed therein, as shown.

Upon its inner or rear face, the lens is preferably provided with an annular flange 6, and all, or practically all, of the light 70 from the lamp 6' passes through that portion of the lens arranged within the flange 6.

The upper portion or half of the lens is provided with spaced vertical ribs 7, cast upon the inner or rear face thereof. As more 75 clearly shown in Fig. 3, the ribs 7 have their surfaces curved in cross-section, and the spaces 8 between the ribs are also curved in cross-section. Particular attention is called to the fact that these ribs 7 are not prisms 80 nor do they function as prisms in bending the shafts of light horizontally in any definite direction or directions, but these ribs function to remove the glare from the light passing through the upper portion or half 85 of the lens, thus producing a light which is fused and somewhat dimmed.

The lower portion or half of the lens 6 is provided with substantially horizontal prisms 8', preferably molded upon the inner or rear face thereof. These prisms have upper inclined faces 9, and lower approximately horizontal faces 10. The inclined faces 9 are transparent and function to bend the shafts of light downwardly, causing the 95 same to strike the road bed, at a suitable distance in advance of the automobile, thus providing sufficient light for fast driving and the like. These downwardly bent rays of light cannot shine in the faces of pedestrians and the like and hence the usual blinding effect is not produced.

As is well known, these lenses are usually employed in connection with parabolic reflectors, and shafts of light R and L are 100 produced, see Figs. 1 and 4. The shaft R passes through the inclined transparent face 9 and is bent downwardly and thrown upon the road bed, as hereinabove stated, while the shafts L pass through the lower or hori- 110

zontal face 10 and would be bent upwardly. This upward bending of the shafts L would throw the light in the eyes of pedestrians, and this is believed to be the reason why 5 attempts heretofore made to bend the shafts of light downwardly have not proven wholly satisfactory, since all of the shafts of light were not bent downwardly. The rays L strike the face 16 at an angle of 40° or more. 10 To overcome this disadvantage, I render the horizontal faces translucent or opaque, which may be accomplished by having these faces frosted or painted with translucent or opaque paint. I prefer to have faces 10 15 frosted, as the same provides a granular surface, and is also cheaper. In certain of the claims it will be stated that the faces 10 are treated or provided with light obstructing means, and this expression is intended 20 to cover translucent or opaque means applied to such faces.

As shown in Fig. 2, the horizontal prisms 8' and the vertical ribs 9 preferably meet at a horizontal line passing through the center 25 of the source of light 6', and the uppermost horizontal prism 8' has portions 10', projecting between the ribs.

In use, the shafts of light passing through the upper or vertically corrugated portion 30 of the lens are diffused and the blinding effect removed therefrom. This provides a somewhat dimmed light at or near the automobile. The shafts of light passing through the inclined faces 9 of the prisms 8' are 35 bent downwardly and thrown upon the road bed at a suitable distance from the automobile, while the shafts of light which strike the substantially horizontal faces 10, are obstructed or so dimmed that they cannot 40 produce a blinding effect.

It is to be understood that the form of my invention herewith shown and described is to be taken as a preferred example of the same, and that various changes in the shape,

size, and arrangement of parts may be resorted to without departing from the spirit of the invention or the scope of the subjoined claims.

Having thus described my invention, I claim:

1. A lens having approximately horizontal prisms formed thereon, said prisms having upper angularly arranged transparent light bending faces and lower approximately horizontal faces which are provided 55 with light obstructing means.

2. A lens having approximately horizontal prisms formed thereon, said prisms having upper angularly arranged transparent light bending faces and lower approximately 60 horizontal translucent faces.

3. A lens having its upper portion provided with light dimming means, and its lower portion provided with substantially horizontal prisms, said prisms comprising 65 upper inclined faces which are transparent and lower faces having means to render them light obstructing.

4. A lens having its upper portion provided with light diffusing means, and its 70 lower portion provided with substantially horizontal prisms, said prisms comprising upper transparent inclined faces and lower substantially horizontal faces which are rendered light obstructing.

5. A lens having its upper portion provided with spaced substantially vertical ribs, and its lower portion provided with substantially horizontal prisms, said prisms having upper angularly arranged transparent faces, and lower substantially horizontal faces which are rendered light obstructing.

In testimony whereof I affix my signature in presence of two witnesses.

ALBERT H. FORGER.
